SMOKER'S UTENSILE

Filed Sept. 24, 1928

Inventor

Sanford M. McCurdy.
by Faust G. Campion
Attorney

UNITED STATES PATENT OFFICE.

SANFORD M. McCURDY, OF ADA, OHIO.

SMOKER'S UTENSIL.

Application filed September 24, 1928. Serial No. 308,031.

My invention has for its object to provide an improved combination cigarette package and match box holder and ash tray having a novel means for readily removably securing it to a puncturable material, such as fabric or leather. The invention is particularly applicable for use in connection with automobiles, embodiments of the invention being adapted for ready securement to automobile cushions or upholstering.

The invention may be contained in structures that vary in their details and, to illustrate a practical application of the invention, I have selected a structure containing the invention and shall describe it herein-after. The structure selected is shown in the accompanying drawing.

Fig. 1 of the drawing is a front view of the smoker's utensil selected for purposes of illustration. Fig. 2 is a vertical longitudinal section through the utensil. Fig. 3 is a rear view of the article. Fig. 4 is an end view of the same.

In the particular form of construction shown in the drawing, the invention provides a container that is preferably oblong both in vertical and in horizontal cross sections to provide a smoker's utensil that has sufficient volume for not only carrying a match box and a cigarette package, but also of a sufficient size for conveniently receiving and containing ashes. The container 1 is thus of such a form that it may be located in any convenient position within the car and yet not be an obstacle to the ordinary movements of the riders of the car. The container, moreover, is provided with an attaching means for connecting it to the upholstering or the interior decoration, where such interior decoration is formed of puncturable material. In order to secure the container 1 in any desired convenient position within the car or any other construction, the container is provided with a pair of pins 2 that are secured to the upper rear corners of the container. The lower ends of the pins 2 are sharpened, as at 3, and the pins extend downwardly and are inclined rearwardly at a sharp angle, substantially as shown in Fig. 4. The container 1 is secured by forcing the

pins through the covering of the cushions or upholstering or other puncturable material and moving the container 1 downward so as to push the pins 2 through the supporting material and until the material is crowded into the space between the end of the pin and the back 4 of the container. The material will thus be pinched between the pins 2 and the back 4 of the container. Where the container is secured in an automobile in the manner described, the pinching of the material between the pins and the back 4 will prevent the container from being jounced loose from its connection with the supporting material and yet the container may be readily lifted from the supporting material and removed therefrom.

The container 1 is provided with two partitions 5 and 6. The partitions 5 and 6 are separated from each other a distance which is equal to about the width of a cigarette package and the partition 6 is separated from one of the end walls a distance which is substantially the same as the width of the ordinary safety match box. Preferably, the partitions 5 and 6 are located so that their upper edges are a short distance below the upper edge of the container. The partitions 5 and 6 extend downwardly to a midpoint in the depth of the container 1 and a partition 8 extends horizontally across the lower ends of the partitions 5 and 6 from the partition 5 to the end wall 7 of the container. Thus, the partition 8 forms the bottom of the chamber 9 located between the partitions 5 and 6 and of the chamber 10 formed between the partition 6 and the end wall 7 of the container. It also forms a chamber 11 in the lower part of the container which communicates with the space 12 between the partition 5 and the end wall 13 of the container. The cigarette package may thus be inserted and held in the chamber 9 and a match box may be inserted in the chamber 10 and ashes may be inserted in the relatively small passage-way or space 12 and will drop into the chamber 11 where they may be collected. When convenient, the container 1 may be disconnected from the upholstering or other supporting sheet material and the chamber 11

may be emptied. Because of the narrow passageway 12 and the location of the ashes below the partition 8, the ashes cannot be blown from the chamber 11, which makes the utensil exceedingly desirable to smokers when riding in automobiles. Also, as the chamber 11 is a closed chamber, burning cigarette "stubs" or "butts" deposited in the chamber 11, through the passageway 12, will be extinguished. Thus the undesirable smoke of the cigarette, after it has been discarded, will be eliminated.

For the convenience of obtaining matches from the match box that may be inserted in the chamber 10, the usual protruding member 15 may be secured to the bottom of the chamber 10 so as to maintain the box in a raised position relative to its enclosing shell or envelope, commonly used as a means for covering such match boxes. Also, the end wall 7 is provided with an opening 16 of a size sufficient to permit the scratching of the match on the material commonly located on the sides of such envelopes or shells of safety match boxes.

Thus, by my invention, I have provided an exceedingly efficient utensil for smokers, particularly of advantage when used in automobiles because of its compactness and its convenience.

I claim:

1. In a smoker's utensil, an oblong container having an oblong cross section, a pair of vertical partitions, and a horizontal partition extending from one end of the container and forming the bottoms of two chambers formed by the vertical partitions and forming a chamber beneath the said chambers that communicates with the space between one of the partitions and one of the end walls of the container, the said first named chambers forming receptacles for a cigarette package and a match box and the third chamber forming a receptacle for ashes.
2. In a smoker's utensil, an oblong container having an oblong cross section, a pair of vertical partitions, and a horizontal partition extending from one end of the container and forming the bottoms of two chambers formed by the vertical partitions and forming a chamber beneath the said chambers that communicates with the space between one of the partitions and one of the end walls of the container, the said first named chambers forming receptacles for a cigarette package and a match box and the third chamber forming a receptacle for ashes, the end wall of the container having an opening for ignition of matches by rubbing on the match box side.
60. In witness whereof I have hereunto signed my name to this specification.

SANFORD M. McCURDY.
